UNITED STATES PATENT OFFICE.

EDMUND E. PECK, OF GRAND VIEW ON HUDSON, NEW YORK.

APPARATUS FOR THE MANUFACTURE OF SEATS AND BACKS FOR CHAIRS AND LIKE FURNITURE.

1,140,846.

Specification of Letters Patent.

Patented May 25, 1915.

Application filed April 24, 1914. Serial No. 834,065.

To all whom it may concern:

Be it known that I, EDMUND E. PECK, a citizen of the United States, residing at Grand View on Hudson, in the county of Rockland and State of New York, have invented an Improvement in Apparatus for the Manufacture of Seats and Backs for Chairs and like Furniture, of which the following is a specification.

10 My invention relates to apparatus for making cushioned seats or backs provided with a cover of flexible material, and is particularly adapted for making seats for chairs, but it may be readily employed in 15 making seats and backs for stools, lounges, sofas, and like articles.

I am aware that apparatus has heretofore been employed in the manufacture of chair seats, to tightly press a leather cover and a 20 padding of cushioning material against the face of a wooden bottom and hold the leather taut, while the edges are secured to the bottom. In such apparatus, however, the leather cover is held against movement 25 by fixed clamps and sharp pins, which puncture the leather, and the cover is pressed directly against a surface of wood while the tightly clamped edges are subjected to undue strain and are often badly torn by the sharp 30 pins.

The object of my present invention is to overcome these difficulties, and in carrying out the same I provide a shaper or matrix of suitable material and shape having elastic material stretched across its top, upon 35 which the flexible cover is laid. I also provide a removable clamping frame to hold the edges of the flexible cover against the top edges of the matrix with sufficient tension to prevent undue slipping of the cover, but at the same time to allow a certain degree of movement under pressure to prevent 40 tearing of the material and to permit the flexible cover to stretch gradually, thereby assuring a smooth and correct formation of 45 the cushioned seat without danger of injury to its edges.

The details of construction are hereinafter particularly described.

50 In the accompanying drawings: Figure 1 is a front view, partly in elevation and partly in section, showing my invention and illustrating the parts in the positions occupied when the seat has been pressed to shape.

55 Fig. 2 is a plan view of the matrix and

clamping frame. Fig. 3 is a section on the line y, y , of Fig. 1. Fig. 4 is a front elevation of the clamping frame detached, and Fig. 5 is a front elevation of the matrix, separated from the other parts.

60 1, 2, 3 and 4 represent the supporting frame.

The shaper or matrix rests upon the horizontal member 1 of the frame. This matrix is to be made of a shape according to the 65 shape of the seat or back desired to be constructed, and it may be of any suitable material, preferably of wood. It consists of an exteriorly flat bottom 5, side walls 6 and 7, front wall 8, and back wall 9. The bottom 5 70 preferably extends slightly beyond the exterior of these walls. On the interior of the matrix the side walls converge or are curved toward the center of the top surface of the bottom 5. The top surfaces of the walls 6, 75 7, 8, 9, of the matrix are preferably provided with spaced transverse grooves or recesses 12, to receive rubber bands or strips of elastic fabric 13, which are stretched across the top of the matrix from front to 80 back and from side to side, thus crossing each other, their ends being turned over said walls and secured to the outer surfaces thereof by tacks or in any suitable way. Strips 10 of wood or other suitable material, 85 are placed on top of the walls 6, 7, 8, 9, of the matrix, over the elastic material and are secured thereto by tacks, or in any suitable manner. These strips 10 extend approximately the distance of the interior of the 90 matrix, but do not meet each other, thereby leaving a space 11 at each corner at the top of the matrix.

It will be readily seen that instead of 95 separate bands 13, of elastic material, a single sheet of rubber or elastic fabric might be employed, although I prefer to employ a plurality of crossed elastic bands. In case a single sheet of elastic material is employed, the grooves or recesses 12, would be 100 unnecessary, as the elastic material might be stretched over the smooth upper surface of the walls of the matrix. Neither are said recesses 12 absolutely necessary where a plurality of elastic bands are employed, but I 105 prefer to provide them, so that the top surfaces of the elastic bands will not have too great frictional contact with the under surfaces of the strips 10.

I provide a clamping frame of a shape 110

corresponding to the shape of the top of the matrix. This frame consists of the members 15, 16, 17 and 18, three of these members being rigidly secured together at one end, 5 while the fourth member is hinged at one end to the end of one of the other members, the free end of the hinged member being provided with a hook 19 to engage an eye 20 on the end of one of the fixed members.

10 21 indicates spaced cleats secured to the outer surface of the frame members and extending below the bottoms thereof so that when the clamping frame is placed upon the top of the matrix these cleats lie against the outer surfaces of the walls of the matrix and hold the frame in its proper position.

15 22 indicates a presser block having a shank 23, provided centrally in its top with a socket 24.

20 25 represents an elongated screw having a reduced lower smooth surfaced end, which fits into the socket 24 on the shank 23 of the presser block.

25 The member 2 of the supporting frame has a vertical opening through it centrally of the upright members 3, 4, of said frame.

27 is a boss on the underside of the frame member 2. This boss has a central screw-threaded hole in alinement with the opening in the member 2.

30 28 is a bushing in the upper part of the opening in the member 2, which bushing is interiorly screw threaded. The screw 25 operates within the screw-threaded holes 35 in the bushing 28 and boss 27.

29 is a hand bar by which the screw 25 is turned.

30 30 indicates the cover for the seat, which cover is of leather or other suitable flexible material.

40 31 represents the cushioning material, which may be of any suitable character.

32 is the seat bottom which is preferably of wood.

45 35 It may be solid, but I prefer that the center part be cut away to lighten it, and that this opening be covered on the top (or that part coming in contact with the cushioning material) by a comparatively thin piece of board or other suitable material 33, as shown in Figs. 1 and 3. I also prefer that the bottom 32 be provided with flanges 34, to receive the edges of the flexible cover 30 when they are folded over as shown in dotted lines in Fig. 1.

When a seat is about to be made, the matrix is laid upon the supporting member 1, between the uprights 3 and 4, and in vertical alinement with the screw 25. The flexible cover 30 is then placed over the top of the matrix where it will be held in a horizontal position by the elastic material 13. The clamping frame is then placed in position, thus clamping the edges of the flexible cover 65 upon the upper surfaces of the walls of

the matrix, and forming a receptacle for the cushioning material 31, which is then laid upon the flexible cover. This is fully illustrated in Fig. 3. The seat bottom 32 is then placed upon the cushioning material and the presser block 22 is placed upon the bottom 32, when by turning the screw 25 the parts are pressed into the position shown in Fig. 1. During this operation the flexible cover is stretched gradually, as the elastic material upon which it rests expands, thereby assuring a smooth and perfectly formed cushioned seat, without danger of tearing the edges of the cover, as these edges are only clamped by the clamping frame with sufficient tension to hold them properly in position while the pressure is applied. Now by releasing the hook 19 on the clamping frame, this frame may be withdrawn from the apparatus and laid aside, which gives 85 free access for the workmen to fold over the edges of the flexible cover upon the flanges 34 of the seat bottom where they are secured in any suitable manner, preferably by tacks. The spaces 11 at the corners of the matrix 90 allow for cutting the flexible material at such points to facilitate the folding of its edges.

In making chair backs, by this apparatus, it is preferable that the edges of the flexible cover be left without folding, and that glue or other suitable adhesive material be applied to such edges so that the back board may be pressed thereon, thus securing the cushioned back thereto.

95 It will be understood that by turning the screw 25 in the reverse direction the presser block 22 may be removed and the cushioned chair seat withdrawn from the matrix in a finished condition, when the operation may 100 be repeated upon another seat.

The supporting frame may be of any desired length so that a number of these devices may be arranged thereon adjacent each other, or separated only by the uprights 3 110 and 4.

I claim as my invention:

1. In an apparatus of the character described, the combination of a matrix, elastic material extended across the top thereof and secured thereto, a clamping frame, a presser block, and means for operating said block.

115 2. In an apparatus of the character described, the combination of a matrix, a plurality of longitudinal and transverse elastic bands stretched across the top of said matrix with their ends secured thereto, a clamping frame, a presser block, and means for operating said block.

120 3. In an apparatus of the character described, the combination of a matrix, a plurality of elastic bands stretched across the top of said matrix and secured thereto, a clamping frame fitting the top of said matrix, means for holding said clamping frame 130

in position, said frame clamping the edges of a flexible cover between it and the top edges of said matrix, cushioning material upon said flexible cover, a chair bottom over 5 said cushioning material, a presser block upon said bottom, and means for operating said block.

4. In an apparatus of the character described, the combination of a matrix, a plu-

rality of elastic bands stretched across the top of said matrix with their ends secured thereto, a clamping frame, a presser block, and means for operating said block.

Signed by me this 18th day of April, 1914.

EDMUND E. PECK.
